(57) **CLAIM**

The ornamental design for a watch display box with multi watch winders, as shown and described.

DESCRIPTION

FIG. 1 is a perspective view showing my new design.

FIG. 2 is a front view thereof.

FIG. 3 is a rear view thereof.

FIG. 4 is a right end view thereof.

FIG. 5 is a left end view thereof.

FIG. 6 is a top view thereof.

FIG. 7 is a bottom view thereof.

FIG. 8 is a perspective view showing an open position thereof.

FIG. 9 is a perspective view in an open position showing the operation of the watch winders thereof; and,

FIG. 10 is a perspective view in an open position thereof, showing the watches displayed.

The broken lines shown in FIG. 10 form no part of the claimed design.
